UNITED STATES PATENT OFFICE.

JAMES ARTHUR SCHOOLING, OF FRANKFORT, INDIANA.

MINER'S-LAMP KIT.

1,355,007.

Specification of Letters Patent.

Patented Oct. 5, 1920.

Application filed January 15, 1920. Serial No. 351,658.

To all whom it may concern:

Be it known that I, JAMES ARTHUR SCHOOLING, a citizen of the United States of America, residing at Frankfort, in the county of Clinton and State of Indiana, have invented new and useful Improvements in Miner's-Lamp Kits, of which the following is a specification.

The object of the invention is to provide 10 a simple and inexpensive attachment for miner's lamps and lanterns designed to contain those articles which are essential to the maintenance of the lamp in a working condition and to permit of lighting the same in 15 an emergency, under such conditions as to avoid loss of time and other inconvenience to the miner and dispense with the disadvantages incident to carrying such essential supplies independently of the lamp, and to 20 this end the invention consists in a construction and combination of parts of which a preferred embodiment is shown in the accompanying drawings, wherein:

Figure 1 is a view of the kit applied in 25 the operative position to a miner's lamp.

Fig. 2 is a detail sectional view of the same.

Fig. 3 is a perspective view of the keeper or support by which the kit is mounted upon 30 the lamp reflector or other convenient part of the device.

The kit consists essentially of a tubular receptacle fitted at opposite ends with removable caps 11 and 12 of which the former 35 preferably carries a needle 13 adapted to serve as a lamp burner cleaner or reamer.

The interior of the casing is divided by a partition 14 to form a main compartment 15 which in addition to inclosing the needle 40 may be employed as a receptacle for matches, and a secondary compartment 16 in which may be stored a flint 17 and an auxiliary, supplemental, or substitute burner tip 18.

Near the upper end of the body portion 45 of the casing there is provided an upstruck rib or bead 19, and the casing is adapted to fit removably in a tubular holder or support 20 having a clamping bracket 21 for

engagement with the reflector 22 or other convenient part of the lamp indicated at 23, 50 the downward displacement of the kit within the holder being prevented by the engagement of the bead 19 with the upper edge of said holder.

It will be seen that the holder engages 55 the casing of the kit at an intermediate portion of its length so that both ends of the kit are exposed and either of the caps fitted upon the terminals thereof may be removed to give access to the desired compartment of 60 the kit and hence the contents of such compartment, without otherwise displacing the device or distributing the contents of the other compartment, so that the miner in the event of the accidental extinguishment 65 of his light may repair or readjust the lamp and relight it without loss of time and therefore without being subject to the inconveniences and dangers which are incidental to mining operations by reason of accidents 70 or mishaps incident to a failure of the lighting means with which such operatives are ordinarily supplied.

What is claimed is:

1. A miner's lamp kit having a tubular 75 receptacle provided with terminal removable caps giving access to the compartments thereof, and a tubular holder for said receptacle provided with means for engagement with a lamp reflector and consisting 80 of a spring bracket, said receptacle being provided with a circumferential bead for engagement with the upper edge of the holder.

2. A miner's lamp kit having a tubular 85 receptacle divided by a partition intermediate of its length to form separate compartments and provided with terminal removable caps giving access respectively to said compartments, a burner cleansing needle 90 carried by one of said caps and adapted to be housed in the compartment closed by said cap, and a holder for the receptacle provided with means for attachment to a lamp.

In testimony whereof I affix my signature. 95
JAMES ARTHUR SCHOOLING.
